(57) **CLAIM**

The ornamental design for a cash drawer, as shown and described.

DESCRIPTION

FIG. 1 is a top plan view of a cash drawer showing my new design;

FIG. 2 is a front elevational view thereof;

FIG. 3 is a rear elevational view thereof;

FIG. 4 is a side elevational view thereof viewed from the left of FIG. 1;

FIG. 5 is a side elevational view thereof viewed from the right of FIG. 1;

FIG. 6 is a perspective view thereof; and,

FIG. 7 is a perspective view thereof wherein the drawer is ejected to an open position and the portions shown in broken lines do not form part of the claimed design.

The bottom plan view forms no part of the claimed design.
